UNITED STATES PATENT OFFICE.

CARL J. PATER, OF WYOMING, OHIO, ASSIGNOR TO THE PHILIP CAREY MANUFACTURING COMPANY, A CORPORATION OF OHIO.

METHOD AND APPARATUS FOR ORNAMENTING MINERAL-SURFACED ROOFING.

Application filed December 3, 1920. Serial No. 427,938.

To all whom it may concern:

Be it known that I, CARL J. PATER, a citizen of the United States, and a resident of Wyoming, in the county of Hamilton, State 5 of Ohio, whose post-office address is 231 Grove Avenue, Wyoming, Ohio, have invented new and useful Improvements in Methods and Apparatus for Ornamenting Mineral-Surfaced Roofing, of which the following is a specification.

My invention relates to method and apparatus for ornamenting prepared roofing, more particularly the ornamenting of mineral surfaced prepared roofing on which the 15 ornamentations are made by compressing the mineral surfacing particles down into and covering them with the coating which before the ornamentation treatment underlies and holds the mineral surfacing particles in place. Roofings of this type are usually made by using a foundation of one or more plies, such as felt, paper, etc., saturated or impregnated with a suitable waterproof material such as asphalt or other 20 bituminous substances and then coating with a suitable waterproofing compound, such as an asphalt compound or other bituminous compound to cover the foundation. Upon this coating is then applied mineral 25 particles of either crushed slate, stone, pebbles, sand, mica or other particles of suitable fire-resisting materials.

Roofings of this type are manufactured and sold without any ornamentations. When 35 these roofings are used where a more decorative surface is desired and they are subjected to an embossing operation wherein a heated design roller is applied to the surface of the mineral particles pressing the 40 particles along predetermined lines down into and covering them with the bituminous coating which has been softened by the heated design roller. In practice it has been found that this ornamenting of the roofing 45 by embossing results in a readjustment or reformation of the roofing along predetermined lines and is facilitated by heating the roofing prior to the embossing operation. This heating of the roofing prior to 50 the embossing operation however tends to cause it to adhere to the foundation on which it rests when the embossing operation is performed; it also stretches the roofing along the edges, and has other objections which I have found can be overcome 55

and the speed of production greatly increased by subjecting the under side of the roofing to a film or coating of liquid or other non-adhesive material preferably cool or cold water.

My improvement prevents the stretching of the roofing along its edges which gives a fluted effect and prevents the roofing from lying flat on the roof when in place.

In the drawings in which like letters refer to like parts, Fig. 1 is a diagrammatic view of the apparatus of my improved apparatus. Fig. 2 is a cross section of Fig. 1 taken on the lines 2, 2 looking toward the right. A is the embossing roll having any suitable raised design on it. This roll is heated preferably by a flame A¹ A¹ which may be located on the inside or outside of the roll or on both, fuel for which is supplied by pipes A² A². Any suitable heating medium may be used. B is the supporting or foundation roll upon which the roofing rests while being embossed. The embossing roll A and the supporting roll B are driven in any desired way, but as shown 70 A is provided with a gear P meshing with a similar gear Q on the shaft of roll B. The gear P is fixed to the shaft of roll A as is also the pulley R driven by belt or otherwise. If desired the roll A is mounted 75 so as to regulate the pressure on the roofing on either or both ends of the roll. C is a continuous belt or carrier adapted to carry the roofing away from the embossing roll. This belt or carrier C is mounted on a series of rollers D, D, one or more of which are operated by suitable source of power so as to keep the belt C in continuous operation. E, E, are cooling drums around 80 which the roofing is passed after the embossing operation for the purpose of cooling it. F is an idler roll to facilitate the rolling up of the roofing after the operation is applied. G is a steam coil or other suitable means for heating the roofing before it reaches the embossing roller. This heating means may be located below the roofing I as shown, or above it or both above and below. I is a roll of mineral surfaced roofing which is being ornamented by my improved apparatus and method. J is a tank or receptacle which contains a suitable liquid, or other material, preferably cool or cold water so that as the foundation roll B rotates in the direction of the arrow it 100 105 110

immerses itself in the water and receives a very light film which it carries up and imparts in part or in whole to the under surface of the roofing simultaneously with the 5 embossing roll treating the opposite surface of the roofing to the ornamenting process. K is a pipe or other inlet from any suitable source of supply, for the receptacle J, having located near the receptacle 10 a valve to control the amount of liquid or other film coating material that enters the receptacle. L is an outlet from the receptacle J having likewise a suitable valve in it to control the amount of film coating material 15 that is passing out of the receptacle other than the amount which is carried out by the rotation of the foundation roll B.

In practice I prefer to use cool or cold water as the film coating material although 20 oil or any other suitable material that will not destroy or effect the under side of the roofing is satisfactory for this purpose. In the use of cool or cold water or other suitable liquid the film, on the foundation roll 25 B, acts to cool the under side of the roofing and prevents its adherence to the foundation roll, while the embossing operation is being performed. In using water or a similar liquid to keep it at an even temperature, 30 or to constantly have a supply of clean liquid, if desired a continuous flow into and out of the receptacle J may be maintained. It is desirable in the ornamenting of the mineral surfaced roofing that the cooling 35 of the under side of the roofing extend not beyond the saturated felt; in other words that the cooling prior to or at the time the embossing operation is performed in no way chills or cools the coating material as the 40 decorating or ornamenting of the roofing depends upon the readjustment of the plastic coating material in predetermined areas to permit and facilitate the mineral surfacing being pressed into and completely covered 45 by the coating.

My improved method of manufacture using the apparatus shown is to take a complete roll of marketable mineral surfaced roofing, subject it to heating process and 50 then pass it between two rolls, one of which has a design on it—the design lines being heated and the under roll having a film of water on it which contacts with the under surface of the roofing, simultaneously with 55 the embossing roll contacting with the upper surface of the roofing, thereby preventing adherence of the roofing to the foundation roll, cooling the roofing on its under surface which permits increase of speed of the 60 operation of the rolls thus facilitating the speed of ornamenting. The liquid film not only acts to prevent the adherence of the roofing to the foundation roller B, but also tends to cool the under surface of the roofing 65 without affecting the temperature of the

coating material which has been softened by the preheating operation. After the embossing operation the roofing is then passed around suitable cooling rolls which act to cool the same from the upper surface. 70

In practice I have found that my improved apparatus and method greatly facilitate the speed of operation of the ornamenting of the roofing while overcoming many of the objections which have heretofore existed in the manufacture of mineral surfaced ornamental roofing. 75

What I claim—

1. In apparatus for ornamenting roofing of the character described, a heated embossing element for forcing the mineral surfacing into the roofing coating, a supporting element for the roofing arranged adjacent to said embossing element, and means for imparting a liquid film to said supporting element. 80

2. In apparatus for ornamenting roofing of the character described, a heated embossing element for forcing the mineral surfacing into the roofing coating, a rotating supporting element arranged adjacent to said embossing element, a liquid containing receptacle in which the said rotating supporting element rotates. 90

3. In apparatus for ornamenting roofing of the character described, a heated embossing element for forcing the mineral surfacing into the roofing coating, a rotating supporting element for the roofing arranged adjacent to said embossing element and means for coating said rotating element with a film of liquid. 95

4. In apparatus for ornamenting roofing of the character described, an embossing element, a rotating supporting element for the roofing arranged adjacent to said embossing element, a liquid containing receptacle in which said rotating element rotates and means for maintaining a flow of liquid thru said receptacle. 105

5. The method of ornamenting roofing of the character described which consists in applying heat to said roofing, applying to one surface of said roofing a non-adhesive film and subjecting the opposite surface of said roofing to a heated embossing element whereby the mineral surfacing is forced into and covered by the roofing coating along predetermined lines. 115

6. The method of ornamenting roofing of the character described which consists in applying heat to said roofing, applying to one surface of said roofing a liquid film and subjecting the opposite surface of said roofing to a heated embossing element whereby the mineral surfacing is forced into and covered by the roofing coating along predetermined lines. 120

7. The method of ornamenting roofing of the character described which consists 130

in applying heat to said roofing, applying to one surface of said roofing a water film and subjecting the opposite surface of said roofing to a heated embossing element whereby the mineral surfacing is forced into and covered by the roofing coating along predetermined lines.

8. The method of ornamenting roofing of the character described which consists in applying heat to said roofing, simultaneously subjecting one surface of the roofing to cooling means and subjecting the opposite surface of said roofing to a heated embossing element whereby the mineral surfacing is forced into and covered by the roofing coating along predetermined lines.

9. The method of ornamenting roofing of the character described which consists in applying heat to said roofing, applying to one surface of said roofing a non-adhesive film and simultaneously subjecting the opposite surface of said roofing to a heated embossing element whereby the mineral surfacing is forced into and covered by the roofing coating along predetermined lines.

10. The method of ornamenting roofing of the character described which con-

sists in applying heat to said roofing, then subjecting said roofing to heat and pressure along predetermined lines while simultaneously subjecting the under surface of said roofing to a supporting element provided with a film of non-adhesive material.

11. The method of ornamenting roofing of the character described which consists in applying heat to said roofing, then subjecting said roofing to heat and pressure along predetermined lines while simultaneously subjecting the under surface of said roofing to a supporting element coated with a film of water.

12. The method of ornamenting roofing of the character described which consists in applying heat to said roofing, then subjecting the opposite surface of said roofing to pressure along predetermined lines while simultaneously subjecting the under surface of said roofing to a supporting element coated with a film of water.

In testimony whereof, I have signed my name to this specification.

CARL J. PATER.
